CONRAD OTT, OF WAYNESBORO, PENNSYLVANIA, ASSIGNOR TO LANDIS TOOL COMPANY, OF WAYNESBORO, PENNSYLVANIA, A CORPORATION

MEANS FOR HOLDING NORMALLY RECIPROCATING SPINDLES FROM RECIPROCATING

Application filed July 29, 1927. Serial No. 209,373.

This invention seeks to provide means for holding a normally reciprocating spindle from reciprocating.

In a grinding machine disclosed in a co-pending application of Scott H. Neady, Ser. No. 120,197, filed July 2, 1926, mechanism is shown for axially reciprocating a shaft carrying a grinding wheel in order to grind the work uniformly and to avoid scratching and marking the same. For grinding a shaft of uniform diameter throughout its length and for a shaft having no shoulders thereon such apparatus is sufficient. If, however, it becomes necessary to grind a shaft having a shoulder thereon or one which has a pulley made integral with the shaft, the apparatus in the above named application is insufficient. In order to grind perfectly the grinding wheel must be permitted to move past the point of grinding. This it cannot do when a shoulder is on the shaft. The shaft up next to the shoulder, therefore, will not be properly ground since the wheel cannot reciprocate beyond the shoulder on the shaft.

The invention in this application seeks to provide means for holding the shaft against reciprocation while the wheel is moved up against the shoulder to grind the shaft up near the shoulder.

Referring to the accompanying drawings which are made a part hereof and on which similar reference characters indicate similar parts,

Figure 1 is a longitudinal sectional view with certain parts left in elevation with the grinding wheel in intermediate position,

Figure 2, an end elevation, and

Figure 3, a side elevation.

Figure 4 is a side elevation showing the grinding wheel at the extreme left against the work.

In the drawings numeral 10 indicates a shaft carrying a grinding wheel 11 for operation upon the work 12 which in this instance is a shaft having a shoulder 13 thereon and the grinding wheel is shown in position to grind the shaft up against the shoulder.

The shaft 10 has thereon a shoulder 14 which abuts against washers 15 and 16 surrounding the shaft between the shoulder and

a flange 17 on a sleeve 18 which surrounds the shaft and provides the medium through which the shaft 10 is reciprocated.

The mechanism for reciprocating the shaft 10 is as follows:

A yoke 19 is pivoted on a pin 20 on the housing of the machine. This yoke carries a pair of arms 21 to which are attached abutting members 22 by means of pins 23. The yoke 19 is provided with a depending bifurcated arm 24 having shoes or bushings 25 in the bifurcation of the end engaging an eccentric 26 carried by a shaft 27. The yoke 19 and the mechanism for giving it a swinging movement is the same as that described in the above named application.

In the sleeve 18 are cup-shaped cavities 28. Adapted to telescope within the cavities 28 are hollow plungers 29. Compression springs 30, attached to the inside of the plunger 29 and the bottom of the cavity 28, provide resilient operative connection between the swinging yoke 19 and the sleeve 18. As the yoke 19 is swung to the right, as shown in Fig. 1, abutments 22 engage the rounded end of the plungers 29 and compress the springs 30. This tends to move the sleeve 18 and the shaft 10 to the right. The sleeve 18 abuts against washers 31 on the shaft 10.

A shoulder 32 on the shaft 10 is engaged by a ring 41 having an inner flange 42 thereon. The ring 41 is held against the shoulder 32 by a lock nut 43.

Pivoted on the frame of the machine at 34 is a lever 35 having bifurcations 36. Pins 37 carrying rollers 38 connect these bifurcations with a spool 39 surrounding the end of the shaft 10. This spool is held in position by a nut 40. The shaft is allowed to rotate in the spool 39 but any axial movement of the shaft must carry with it a corresponding movement of the spool.

From the foregoing description the operation of the device should now be apparent. During normal operation of the machine rotation of the shaft 27 and the eccentric end 26 imparts a swinging movement to the yoke 19. The member 22, pressing against the plunger 29, compresses the spring 30 and this in turn acts upon the sleeve 18 to move the

100

shaft axially to the right as shown in Figure 1. The inner end of each of the pins 23, shown in dotted lines in Figure 1, engages a slot in the sleeve 18. As the yokes 5 19 swing to the left the pins 23 move the sleeve 18 axially to the left to move the shaft 10. This shaft is, therefore, positively moved in one direction by the sleeve 18 abutting the shoulder 14, and resiliently 10 moved in the other direction by the springs 30. When, however, it is desired to operate the grinding wheel without the reciprocating movement, the operator by 15 means of the hand lever 35 holds the shaft 10 in the position shown in Fig. 1. When held in this position the movement of the swinging yoke 19 is taken up by the springs 30 and no reciprocation of the shaft 10 occurs. The wheel 11 may be held in this position as long as desired by the operator or until the shaft up near the shoulder is ground 20 to the desired size. Upon release of the handle 35 the shaft will again be reciprocated as before.

25 It will be obvious to those skilled in the art that various changes may be made in my device without departing from the spirit of the invention, and I, therefore, do not limit myself to what is shown in the drawings and 20 described in the specification, but only as set forth in the appended claim.

Having thus fully described my said invention, what I claim as new and desire to secure by Letters Patent, is:

25 A device of the kind described comprising a shaft, a sleeve on said shaft and adapted to move longitudinally therewith, a socket in said sleeve, a plunger in said socket, resilient means between said plunger and said socket, 40 an arm pivoted at one end and having an abutment for engagement with the plunger, means for swinging the pivoted arm to impart movement to said sleeve and shaft through said resilient means, and manually 45 controlled means for holding the shaft against axial movement during the swinging of said arm, substantially as set forth.

In witness whereof, I have hereunto set my hand at Waynesboro, Pennsylvania, this 50 22nd day of July, A. D. nineteen hundred and twenty-seven.

CONRAD OTT.
